UNITED STATES PATENT OFFICE.

ARTHUR ATWATER KENT, OF ARDMORE, PENNSYLVANIA.

IGNITION APPARATUS.

Application filed July 27, 1921. Serial No. 487,994.

My invention relates to apparatus utilizable in connection with the electrical ignition system of an internal combustion engine, and particularly such as employed upon automobiles or other motor vehicles.

In accordance with my invention, the ignition circuit, as the primary circuit of a spark producing induction coil, is interrupted or controlled by timer or interrupter contacts whose co-action is effected by a cam, or equivalent, driven by a shaft of the engine, as the engine cam shaft, through suitable gearing, or equivalent, advance or retardation of the ignition sparks being effected by bodily rotating the interrupter structure with its cam, or equivalent, about the axis of said engine shaft.

Further in accordance with my invention, the cam rotates about an axis which is disposed at a relatively great angle, as a right angle or approximately a right angle, with respect to the axis of the engine shaft which drives the cam and which is preferably offset from or does not intersect the axis of the engine shaft, and advance and retardation of the ignition is effected by so actuating the structure that the axis of rotation of the cam is rotated about the axis of said engine shaft.

Further in accordance with my invention, the cam, or equivalent, is automatically angularly adjusted with respect to its axis of rotation by speed responsive means, as a centrifugal governor, for automatically advancing or retarding ignition, the interrupter and cam structure, together with the speed responsive means, being additionally movable, as aforesaid, about the axis of the engine shaft for effecting manual advance or retardation of the ignition.

My invention resides in structure of the character hereinafter described and claimed.

For an illustration of one of the various forms my invention may take, reference is to be had to the accompanying drawings, in which:

Fig. 1 is an end elevational view of apparatus embodying my invention.

Fig. 2 is a longitudinal section, some parts on the line 2-2 of Fig. 1.

Fig. 3 is a sectional view, partly in plan, taken on the line 3-3 of Fig. 1.

Fig. 4 is a sectional view, partly in plan, on the line 4-4 of Fig. 3.

Fig. 5 is a cross sectional view on the line 5-5 of Fig. 2.

Fig. 6 is a fragmentary view illustrating the interrupter or contact structure in association with the cam.

The apparatus hereinafter described, and constituting only one example of my invention, constitutes ignition timing and controlling apparatus adaptable to the four cylinder engine of the Ford automobile, in lieu of the standard Ford ignition control comprising a primary circuit commutator or timer driven by the cam shaft of the engine.

Referring to the drawings, 1 represents any suitable stationary supporting member, and in the example illustrated will be recognized as the forward end casting or plate covering the timing gear case of a Ford engine whose main or crank shaft is indicated at 2, Fig. 1, and whose cam shaft, driven by timing gears from the shaft 2, is indicated at 3 having a bearing in the member 4 supported in the member 1.

A casing 5, supplanting the Ford commutator or timer casing, abuts against the bearing surface 6 and engages within the circular bearing rib 7 with respect to which the casing 5 is rotatable about the axis of the shaft 3. Integral with or secured to the casing 5 is the upwardly extending bracket or housing member 8 terminating at its upper end in a casing 9 at or adjacent which is a bearing for the timer shaft 10, for which there is provided adjacent its lower end the bearing 11 carried by or integral with the members 5 and 8. At the lower end of the member 8 is an enlargement 12 having at its lower end in alignment with the shaft 10 an opening 13 closed by the removable cap 14. Within the chamber 12 there is disposed the gear 15 which, as illustrated, may be a spiral gear or which may be a bevel or any other suitable type of gear, meshing with and driven by a spiral or other suitable gear 16. The gears 15 and 16 have equal numbers of teeth whereby the shaft 10 rotates at the same speed as the cam shaft 3, that is, at a speed one-half the speed of the main or crank shaft 2, in the case of a four cycle or four stroke engine.

The cap or casing 5, and the parts carried thereby, are held in position by the spring finger 17 secured by bolt 18 upon a lug 19 adjacent the oil filler 20, the cap 5 having an axial depression 21 in which engages the button 22 upon the spring finger 17, the finger 17 being such as employed upon a standard Ford equipment for hold-

ing the commutator or timer casing. Such timer casing is supplanted, as shown, by the cap or casing 5 which, with the bracket 8 and parts carried thereby, may be rotated about the axis of the shaft 3. For this purpose is provided a rod or other member 23, Fig. 1, connected at one end to means actuated by the spark advancing and retarding lever upon the steering wheel, and attached at its other end at 24 to the lug 25 upon the member 8 or casing 9.

The shaft 10, at its upper end, drives any suitable type of interrupter or timer structure. In the example illustrated, this structure comprises a stationary interrupter contact 26 mounted upon the member 27 held by screw 28 to the plate or cover member 29 secured by screws 30 to the upper edge of the casing 9. Co-acting with the stationary contact 26 is the movable contact 31 carried by the arm 32 supported by spring 33 upon the member 34 suitably mounted upon the plate 29. The arm 32 carries a shoe 35, which engages the cam 36 loose upon the upper end of the shaft 10, upon whose end above the cam 36 is carried in fixed relation to the shaft 10 the distributor block 37 having the terminal 38 rotated by the shaft 10 in succession past high tension distributor terminals 39, one for each cylinder of the engine and equally circumferentially spaced, and forming extensions upon inserts 40 molded within the cap 41 secured in fixed position upon the plate 29, and therefore in fixed position upon the casing 9, by any suitable means, as spring hooks 42, Fig. 1, pivoted to the casing 9 at 43 and engaging the cap 41. To the distributor terminal 38 is connected the spring contact 44 engaging the axial contact 45 in the insert 46 molded in the cap 41. In the socket of the insert 46 is adapted to engage the end of a flexible cable whose other end connects to the high tension secondary of an ignition or spark producing induction coil; and in the sockets of the inserts 40 engage ends of flexible high tension cables leading, respectively, to the spark plugs of the different cylinders of the engine. The cam 36 may be fixedly secured to the shaft 10; in the example illustrated, however, it is loose upon the shaft 10 and is angularly advanced, in response to speed changes, by governor mechanism, such, for example, as illustrated in my pending application Ser. No. 525,936, filed December 30, 1921, and comprising the governor plate 47 secured to the shaft 10, suitable weight structure 48 being pivoted upon the plate 47 and acting under centrifugal force to rotate the plate 49 about the axis of the plate 10 and thereby angularly adjust the cam 36, which is secured to the plate 49.

As indicated in Fig. 2, the axis of the

shaft 10 is offset from and forms a great angle with the axis of the shaft 3, it being understood that the angle between the axes of the shafts 10 and 3 may be a right angle, or any other suitable angle. By the aforesaid offset of the cam shaft 10 its axis is not parallel to and does not intersect the axis of the engine shaft 3.

As indicated in Fig. 1, the timing structure may be swung to right or left about the axis of the shaft 3, the extent of movement being limited only by adjacent parts, if any. In the example illustrated, the swinging movement to right or left is limited, on the one hand, by the edge 50 of the oil filler 20, in the case of a Ford engine, and on the other hand, by the lower end 51 of the fan-carrying arm 52, adjustable about the bolt 53 by the adjusting screw 54 engaging upon the heel 55 of lever 52; the screw 54 is adjustable in the lug 54^a, carried by the supporting member 1, to clear which, and for any other suitable purpose, the axis of shaft 10 and bracket 8 is inclined forwardly or toward the left, as viewed in Fig. 2, whereby the axis of the shaft 10, in the example illustrated, is inclined at more than ninety degrees with respect to the axis of the shaft 3.

Without limiting my invention thereto, but by way of example, it is preferred that the number of teeth in the gear 15 shall be relatively great and shall be an odd number when, as is general practice, the number of cam faces is even, whereby the number of teeth of the gear 15 divided by the number of cam faces leaves a fractional remainder. In the example illustrated, each of the gears 15 and 16 has fifteen teeth, and with a four-faced cam, as illustrated, there are three and three-quarters teeth per cam face. The advantage of such an arrangement lies in the fact that it facilitates the attainment of proper normal setting of the cam 36 with respect to the shaft 3, and therefore with respect to the engine pistons, in the so-called "timing" of the ignition apparatus with the engine at rest. It is generally desirable that the "timing" or normal setting of the cam 36 with respect to shaft 3 shall be such that the interrupter contacts 31 and 26 are at the point of separating with the bracket 8 in a position which still permits sufficient range of movement in direction for ignition retardation. If this relation does not obtain, with the gear 15 out of mesh with the gear 16, the cam may be rotated 90 degrees (in the case of a four-faced cam) in the direction in which it normally rotates, and to bring the gear 15 again into mesh with gear 16 it will be necessary to rotate the cam and shaft 10 through an angle corresponding with a fraction of a tooth of the gear 15, and so either attain or more closely approximate the desired setting. If the desired setting

has been only more nearly approximated by the rotation of the cam through 90 degrees, it may be rotated through another 90 degrees, in which case again the gears will not be 5 in position to mesh with each other, but will require a further movement of the cam and shaft 10 to procure a mesh resulting in the setting of the cam 36 either at or more nearly the desired position. An so on, by 10 successively moving the cam through a quarter of a revolution, suitable timing will eventually be attained.

The operation is as follows:

First assuming the engine at rest, it will 15 be noted that by swinging the bracket 8 toward the right or left, thus rotating the structure about the axis of the shaft 3, the gear 16, also at rest, enforced rotation of the gear 15 through an angle corresponding 20 with the angle of movement of the bracket 8. Accordingly, the shaft 10 rotates through similar angle, carrying the cam 36 with it through the same angle (the governor being 25 inactive), and since the cam 36 is so rotated by swinging the arm 8, one of its angles or 30 points adjacent the shoe 35 will approach or recede from the shoe. That is to say, by such angular movement of the cam 36 due to 35 swinging of the member 8, the relation of the cam to the movable interrupter arm 32 is changed, causing earlier or later separation of the movable contact 31 from the stationary contact 26, and so advancing or retarding the production of a spark, which occurs upon separation of contact 31 from contact 26.

Now assuming the engine to be in motion, the shaft 10 rotates at a speed equal to the speed of the shaft 3, and the cam 36 (neglecting the effect of the governor) periodically 40 separates the interrupter contacts. If, now, while the engine is running, the bracket 8 be swung to right or left and so rotate the mechanism about the axis of the shaft 3, 45 which is rotating, the cam 36 will be correspondingly advanced ahead or retarded behind the shaft 10, as described in the case where the engine was at rest. It follows, therefore, that while the engine is running 50 the ignition may be advanced or retarded by swinging the arm 8 in the one direction or the other about the axis of the shaft 3.

With increasing speed, the weight structure of the governor moves further and 55 further from the axis of the shaft 10 and advances the governor plate 49 with respect to the governor plate 47, thereby advancing the cam 36 with respect to the shaft 10, such action of the governor being additional to 60 any advance or retardation effected by swinging the arm 8 to right or left, as viewed in Fig. 1.

What I claim is:

1. Ignition timing apparatus comprising a 65 rotatable shaft, a bracket member, a casing

thereon, a member disposed above the bottom of said casing, ignition timing contacts carried by said member, a second shaft extending at a great angle with respect to said first shaft and supported by said bracket 70 member, a driving connection between said shafts, a timing member controlling said contacts, a centrifugal governor in said casing intervening between said second shaft and said timing member for angularly adjusting 75 the same with respect to said second shaft, a cap carried by said casing and carrying high tension terminals, a rotatable distributor within said cap co-acting with said terminals, said cap, contact-carrying member and 80 casing being fixed against rotation about the axis of said second shaft, and means for adjusting said second shaft about the axis of said first shaft for adjusting the timing of ignition. 85

2. Apparatus for controlling the ignition of a multicylinder engine comprising a rotatable multi-faced timing member, as a cam, a shaft for rotating said member, a second shaft noncoincident with said first shaft, a gear on said first shaft having teeth whose number is prime to the number of faces of said timing member, and a gear on said second shaft driving said first named gear, said timing member and said first shaft adjustable as a unit about the axis of said second shaft for adjusting the timing of ignition. 95

3. The combination with a rotatable timing member, as a cam, and ignition controlling contacts controlled by said timing member, of a shaft whose axis of rotation is offset from and at an angle greater than a right angle with respect to the axis of rotation of said timing member, and a driving connection between said shaft and said timing member, said timing member and contacts being adjustable as a unit about the axis of said shaft for adjusting the timing of ignition. 100

4. The combination with a pair of casings spaced from each other, a bracket carrying one of said casings and carried by another of said casings in fixed position with respect thereto, a cam and ignition controlling contacts controlled by said cam, housed in said one of said casings, of a shaft for rotating said cam, a second shaft, a driving connection between said shafts and housed by the other casing of said pair, said first named shaft and bracket being concentric and disposed at an angle greater than a right angle with respect to the axis of said second shaft, and means supporting said other of said casings for rotatable adjustment about the axis of said second shaft for adjusting the timing of ignition. 115

5. The combination with a pair of casings spaced from each other, a bracket joining said casings, a cam and ignition controlling contacts controlled by said cam, housed in 120 125 130

one of said casings, of a shaft for rotating said cam, a second shaft, a driving connection between said shafts and housed by the other casing of said pair, means supporting

5 said other of said casings for rotatable adjustment about the axis of said second shaft for adjusting the timing of ignition, and means movable as a unit with said casings and bracket for adjusting the timing of ignition independently of the aforesaid adjustment.

6. The combination with a pair of casings spaced from each other, a bracket joining said casings, a cam and ignition controlling

15 contacts controlled by said cam, housed in one of said casings, of a shaft for rotating said cam, a second shaft, a driving connection between said shafts and housed by the other casing of said pair, means supporting

20 said other of said casings for rotatable adjustment about the axis of said second shaft for adjusting the timing of ignition, and speed responsive means in said first named casing for varying the position of said cam

25 with respect to said first named shaft and adjustable as a unit with said casings and bracket.

7. Ignition timing apparatus comprising a stationary supporting member, a rotatable shaft, a gear on the end thereof, a casing open at its one end and enclosing said gear and rotatable on said supporting member about an axis coincident with the axis of said gear, a second shaft carried by said

35 casing and extending at a great angle with respect to the axis of said first shaft, ignition controlling apparatus operated by said second shaft and carried by said casing, means holding said casing against said sup-

40 porting member and permitting rotatable adjustment of said second shaft about the axis of said first named shaft, a driving connection between said shafts disposed within said casing and comprising said first named

45 gear and an intermeshing gear secured upon said second shaft, and means applied at a point remote from said casing and adjacent said timing apparatus for moving said timing apparatus, casing and second shaft as a unit for advancing and retarding ignition.

8. The combination with a stationary supporting member, of a casing bearing against and rotatably adjustable upon said supporting member, timing apparatus carried by

55 said casing, a shaft about whose axis said casing is rotatably adjustable, and a gover-

nor for automatically advancing at retarding ignition driven by said shaft and adjustable as a unit with said casing.

9. Ignition timing apparatus comprising 60 a rotatable shaft, a bracket member, a casing thereon, a cover for said casing, ignition timing contacts carried by said cover, a second shaft extending at a great angle with respect to said first shaft and supported by 65 said bracket member, a driving connection between said shafts, a timing member controlling said contacts, a centrifugal governor in said casing intervening between said second shaft and said timing member for angularly adjusting the same with respect to said second shaft, a cap surmounting said cover and carrying high tension terminals, a rotatable distributor within said cap co-acting with said terminals, said cap, cover 70 and casing being fixed against rotation about the axis of said second shaft, and means for adjusting said second shaft about the axis of said first shaft for adjusting the timing of ignition. 75

10. The combination with a rotatable timing member, as a cam, and ignition controlling contacts controlled thereby, of a shaft whose axis of rotation is disposed at a great angle with the axis of rotation of said timing member, a driving connection between said shaft and timing member, said timing member and contacts being adjustable as a unit about the axis of said shaft, and means for changing the timing of ignition 80 while said unit remains fixed in one of its positions of adjustment about the axis of said shaft. 85

11. Ignition timing apparatus comprising a stationary supporting member, a rotatable shaft, a casing bearing against and rotatable upon said supporting member about the axis of said shaft, a second shaft supported by said casing, timer contacts and a timer cam therefor supported by said casing, said 100 cam driven by said second named shaft, a driving connection between said shafts, and means for moving said casing, contacts and timer cam as a unit about the axis of said first named shaft while said shafts are in 105 rotation for advancing or retarding ignition.

In testimony whereof I have hereunto affixed my signature this 19th day of July, 1921.

ARTHUR ATWATER KENT.
